SKATING RINK

Alvin H. Baer and Edward B. McCabe, Carbon-dale, Pa., assignors, by mesne assignments, to Worthington Pump and Machinery Corporation, Harrison, N. J., a corporation of Virginia

Application June 22, 1934, Serial No. 731,816

14 Claims.

(Cl. 62—12)

The ordinary swimming pool is usually out of use in the wintertime, while the ordinary outdoor ice skating rink cannot be used in the summertime.

One object of the present invention is to provide means whereby a pit, regularly or irregularly formed, may be easily converted into an artificial ice skating rink.

Another object of the present invention is to provide a new and improved construction whereby a pit may be converted into a swimming pool or an artificial ice skating rink in a comparatively short time.

It has been proposed to provide a pan which carries a series of freezing pipes, and which extends across substantially the entire area of a pit. This pan is adapted to be sunk to the bottom of the pit when the latter is to be used as a swimming pool, or floated to a position near the top of the pit when said pit is to be converted into an ice skating rink. In this latter position, a layer of water in the floated pan is frozen solid by the freezing pipes to form an ice skating floor. In a construction of this type, the pan breaks up the continuity of the inner surface of the pit when the latter is used as a swimming pool, and materially reduces the swimming space in said pit.

Also, when the pan is floated in position to form an ice skating floor, the whole body of water upon which the pan is floated is cooled by the freezing pipes, so that a great deal of the refrigerating action of said pipes is lost.

Furthermore, precaution must be taken to prevent sinking of the pan resulting from overload or leakage through the pan.

As an important feature of the present invention, there is provided an easily mountable and demountable skeleton frame structure supported in the pit from the floor thereof. We provide one or more evaporator pipe sections which may be supported upon the frame structure, and which may be easily conveyed to or from the pit. In the winter, when it is desired to use the pit as a skating rink, the skeleton frame structure is assembled in the pit and the evaporator sections supported upon said frame structure below the top of the pit. The pit is then filled with water to a level above the evaporator sections, and the refrigerating system operated to freeze the water around said sections. A solid block of ice of substantial thickness will be formed extending across the entire area of the pit, and surrounding the evaporator sections. The ice block will span the gaps between adjoining pipe

sections so as to hold said sections against horizontal displacement, and will present a continuous horizontal smooth skating surface. Furthermore, the ice block will be positively supported against accidental sinking.

After a block of ice of substantial thickness has been formed, the level of the unfrozen water in the pit below said ice block is dropped low enough to avoid or retard any further freezing of said water from the pipe sections or the cold atmosphere above, so that the power necessary to form and maintain the desired ice skating surface is reduced to a minimum.

At the end of the skating season, the refrigerating system is shut down, the water drawn out of the pit, the evaporator section or sections removed, and the frame structure disassembled. This takes but a short time and only a small amount of labor. The pit will then be in condition for swimming.

As a further feature of the present invention, the return main of all the evaporator pipe sections is provided at its outlet with a pressure control valve for sustaining a predetermined pressure, so that there is an equal evaporating temperature throughout all of the evaporator sections, and the rate of freezing for the entire ice floor will be uniform throughout. Furthermore, the texture of the ice formed will be greatly improved thereby.

As another feature, the present construction is provided with means for forming and maintaining the skating floor by the circulation of a volatile refrigerant in direct heat exchange relationship with said floor. Hitherto, the successful freezing of the skating floor has been attained only by the circulation of brine previously cooled in separate vessels by the direct expansion of the volatile refrigerant.

In the accompanying drawings, there is shown for the purpose of illustration, one embodiment of the present invention. In these drawings:

Fig. 1 is a top plan view, somewhat diagrammatic, and partly in section, of a swimming pool which has been converted into a skating rink.

Figs. 2 and 3 are sections taken on the lines 2—2 and 3—3 respectively, of Fig. 1, with the skeleton frame structure shown somewhat diagrammatically.

Fig. 4 is a plan view, partly in section, showing details of the pipe sections somewhat enlarged.

Fig. 5 is a section taken on the line 5—5 of Fig. 1, but somewhat enlarged.

Fig. 6 is a top plan view showing in detail a portion of the refrigerating system, and

Fig. 7 is a side view of a part of the refrigerating system.

In the specific embodiment of the present invention, there is provided a pit 10 which is shown of the ordinary construction customary in swimming pools, and which may have a bottom which slopes lengthwise so that one end of the pool is shallow while the other end is much deeper.

The skeleton frame structure for supporting the evaporator sections may be of any suitable construction in which the members or sections are bolted together to permit them to be easily mounted in position when the pit is to be converted into a skating rink, and to be easily disassembled and removed when it is desired to use the pit for a swimming pool. In the form shown, this frame structure comprises a series of upstanding posts 11 suitably braced and resting upon the pit floor. Secured to the upper ends of the posts 11 are suitable horizontal beams 12.

The refrigerating system includes a plurality of evaporator sections 13, each advantageously comprising a pipe 14 serpentined as shown, and provided with inlets 15 and outlets 16 on the same side of the section. Each evaporator section is advantageously connected to wooden cross beams 17 by any suitable means as for instance straps 18 straddling the pipe 14, and secured to said cross beams by nails or screws. The evaporator sections are supported on the frame structure with the cross beams 17 resting on said structure as shown.

For an ordinary swimming pool each evaporator section 13 extends from one side of the pit to a region substantially midway of the pit as shown in Fig. 1, so that there are provided two series of these sections on opposite sides of the longitudinal center line of the pit.

Extending along each side of the pit is a feed header 19 connected to the inlet 15 of each evaporator section 13 through a pipe 21. Also extending along each side of the pit is a return header 22 connected to the outlet of each evaporator section 13 through pipes 23. The connections between the headers and the evaporator sections are effected through easily disconnectible couplings.

In order that the feed and return headers may be concealed from view, there is provided along each side of the pit 10 a trench 24 having a suitable cover 25. The headers 19 and 22 extend in said trenches 24 and may be supported on suitable piers 26 in the interior thereof.

The pipe connections 21 and 23 between the evaporator sections and the headers 19 and 22 are shown extending upwardly along the side walls of the pit, over across the tops of the side walls, and downwardly into the trenches 24. If desired, a suitable molding or curbing may be positioned around the periphery of the pit alongside of the portions of the pipes 21 and 23 extending upwardly in the inner sides of the pit to conceal said pipes and to form a dasher board against which a hockey puck may be hurled.

As an important feature of the present invention, the pipes 14 of the evaporator sections 13 have cores 27 extending axially through said pipes to form annular chambers 28. These cores may extend only through the straight portions of the pipes as shown, or may extend throughout the entire lengths thereof including the bends or headers. By means of this construction, the refrigerant will flow in a stream having an annular cross-section, and will have increased velocity, so that the rate of evaporation will be greatly im-

proved and the gases resulting from the evaporation may be cleared from the pipes as they are formed.

The refrigerating system includes a liquid refrigerant or gas flash chamber 30 having a return pipe 31 leading to the upper portion thereof from the outlets of the return headers 22. The chamber 30 also has a gas outlet 32 leading from the top thereof to the liquefying apparatus such as a compressor, (not shown).

As an important feature of the present invention, the return pipe 31 is provided with a pressure control valve 33 acting as a yieldable restricting aperture in the return pipe, which passes both liquid and gas refrigerant to the chamber 30 where the gas and liquid separate. The gaseous refrigerant goes to the compressor (not shown) while the liquid refrigerant is pumped through the freezing sections. The valve 33, acting as a yieldable restriction in the return pipe, sets up just enough resistance so that all of the coils or freezing sections will be full of a mixture of flowing gas and liquid at all times, thereby maintaining complete distribution of the freezing sections and the surface of the coils or sections will be wetted with flowing refrigerant and functioning at its fullest capacity as a freezing surface.

The pressure control valve 33 may be of any approved type such as may be purchased upon the open market.

The liquid refrigerant is supplied by a conduit 35 and the level of the liquid in the receiver 30 is controlled by any suitable means as for instance a float control valve within a float chamber 34 communicating with the bottom and top of the chamber 30 through pipes 36 and 37. The liquid from the chamber 30 is delivered to the evaporator sections 13 by a pump 38 driven through a suitable source of power such as a motor 39, and having its inlet connected to the bottom of the chamber 30 through a pipe 40.

The main portion of the refrigerating system may be located at any suitable place, for instance in a machinery room A near the pit 10 as shown in Fig. 1.

In the winter, when it is desired to use the pit 10 for a skating rink, the skeleton frame structure is assembled and supported upon the floor of the pit. The evaporator sections are then supported close to each other in position over the skeleton frame structure, and their respective inlets and outlets connected to their respective feed and return headers 19 and 22 respectively. Water is then introduced into said pit to a level above the evaporator sections 13. The refrigerating system is then started to freeze the water surrounding the sections until a solid floor of ice 42 of substantial thickness has been formed. The gaps between adjoining sections will be filled by the ice block and the ice skating surface will be continuous throughout the whole area of the pit. The level of unfrozen water in the pool is then dropped to avoid any further freezing from the refrigerant or the cold atmosphere above.

Although the invention is shown as particularly adapted to convert an ordinary swimming pool into a skating rink and vice versa, the invention, as far as certain of its aspects are concerned, is equally adapted to convert any large outdoor pit into an artificial ice skating rink. In such cases, for instance, the pit may be lined with concrete and filled with cinders up to a certain level. The evaporator sections previously described may be supported on said cinders with the wooden cross beams 17 partially embedded in

said cinders to space said sections above said cinders. The space between the cinders and the evaporator sections may be filled with fine material such as sand. In forming the ice-skating surface, water is introduced into the pit to a substantial height above the evaporator sections, and a solid ice block formed as already described. With such a construction, the cinders and sand do not have to be removed at the end of the 10 skating season.

Although the present construction is shown as provided with a refrigerating system in which a volatile refrigerant is circulated in direct heat exchange relationship with the skating floor to 15 be frozen, as far as the broad aspects of the invention are concerned, other refrigerant may be used for directly cooling said skating floor. For instance, a refrigerant such as brine may be cooled in a suitable cooling device forming part 20 of the refrigerating plant, and then circulated by a pump in heat exchange relationship with the skating floor.

Having thus described our invention, what we claim as new and desire to secure by Letters

25 Patent is:—

1. In combination a pit adapted to be used as a swimming pool, an easily mountable and demountable frame structure supported in said pit, a pipe section horizontally supported on said 30 frame structure below the top of said pit and easily detachable from said frame structure, means for introducing a freezing medium through said pipe section to freeze a body of water above said section into a solid ice block, and means 35 for sustaining the freezing medium at a predetermined pressure in said pipe section.

2. In combination an easily mountable and demountable frame structure adapted to be supported in a pit, a plurality of freezing sections 40 horizontally supported on said frame structure in close relationship to each other and below the top of said pit, said freezing sections being easily detachable from said frame structure, means for introducing a refrigerating agent through said 45 freezing sections to freeze a body of water above said sections into a solid ice block extending substantially across the entire area covered by said sections, and means for sustaining equal freezing temperature throughout all of said sections.

50 3. A convertible swimming pool and skating rink, including a pit large enough to serve as a swimming pool, a frame structure easily mountable and demountable and supported in said pit, a plurality of freezing sections horizontally supported on said structure below the top of said pit and easily detachable therefrom, said sections conjointly extending substantially throughout the entire area of said pit, means for introducing a refrigerating agent through said freezing sections to freeze a body of water surrounding said 55 sections into a solid ice block extending substantially across the entire area of said pit, and means for sustaining equal freezing temperature throughout all of said sections.

60 4. A convertible swimming pool and skating rink including a pit large enough to serve as a swimming pool, a frame structure easily mountable and demountable and supported in said pit, a feed header, a return header, a plurality of freezing sections horizontally supported on said structure below the top of the pit, easily detachable therefrom, and connected in parallel to said headers, and a pressure control valve at the outlet of said return leader for sustaining a volatile refrigerant under a predetermined pressure throughout 65

all of said freezing sections, so that equal freezing temperature is maintained throughout all of said sections.

5. A construction for forming an artificial ice skating surface, comprising a freezing section including one or more pipes having cores extending axially therein to form annular chambers, means for supporting said freezing section horizontally in a pit, means for circulating a volatile refrigerating agent through said annular chamber to 10 freeze a body of water into a solid ice block presenting an ice skating surface, and means for setting up a limited amount of resistance to flow of refrigerant through said chamber.

6. The method of converting a swimming pool 15 into an artificial skating rink, including the steps of horizontally supporting a freezing coil below the top of the swimming pool, filling the pool with water to a level above said coil, circulating a freezing agent through said coil to 20 form a solid block of ice surrounding said coil, and then lowering the unfrozen level of water in said pool to form an air space below said ice block.

25 7. In combination, a pit adapted to be used as a swimming pool, an easily mountable and demountable frame structure supported in said pit, a pipe section horizontally supported on said frame structure below the top of said pit and easily detachable from said frame structure, said 30 pipe section including a return pipe having a restricting aperture therein, and means for creating a forced circulation of volatile liquid refrigerant through said pipe section and restricting 35 aperture.

8. In combination, a pit adapted to be used as a swimming pool, an easily mountable and demountable frame structure supported in said pit, horizontal freezing sections removably supported on said demountable frame at a level below the 40 top of said pit, inlet and outlet headers joining said freezing sections, means for creating a forced circulation of a volatile liquid refrigerant through said sections, and means setting up a limited amount of resistance to flow of said refrigerant 45 for maintaining complete distribution of refrigerating liquid through all said sections.

9. In combination, a pit adapted to be used as a swimming pool, an easily mountable and demountable frame structure supported in said pit, 50 horizontal freezing sections removably supported on said demountable frame at a level below the top of said pit, inlet and outlet headers joining said freezing sections, means for creating a forced circulation of a volatile liquid refrigerant through 55 said sections, a return pipe from said sections to said means, and means in said return pipe forming a yieldable resistance to the flow of liquid therethrough.

60 10. In combination, an easily mountable and demountable frame structure adapted to be supported in a pit, a plurality of freezing sections horizontally supported on said frame structure in close relationship to each other and below the top of said pit, a receiver, means for creating 65 from said receiver a forced circulation of volatile liquid refrigerant through said freezing sections, a return pipe for returning the refrigerant to said receiver, and means setting up a limited amount of resistance to flow of said liquid for 70 maintaining complete distribution of refrigerating liquid through all said sections.

11. In combination, an easily mountable and demountable frame structure adapted to be supported in a pit, a plurality of freezing sections 75

horizontally supported on said frame structure in close relationship to each other and below the top of said pit, a receiver, means for creating from said receiver a forced circulation of volatile liquid refrigerant through said freezing sections, a return pipe for returning the refrigerant to said receiver, and a yieldable restricting valve in said return pipe.

12. A convertible swimming pool and skating rink including a pit large enough to serve as a swimming pool, a frame structure easily mountable and demountable and supported in said pit, a feed header, a return header, a plurality of freezing sections horizontally supported on said frame structure below the top of the pit easily detachable therefrom and connected in parallel to said headers, and means at the outlet of said return header setting up a limited amount of resistance to flow of refrigerant so that equal freezing temperature is maintained throughout all of said sections.

13. In combination, a pit large enough to serve as a swimming pool, an easily mountable and demountable frame structure in said pit, a feed header, a return header, a plurality of freezing sections supported on said frame structure below the top of said pit and connected to said head-

ers, a receiver connected to the outlet of said return header, means for creating from said receiver a forced circulation of refrigerant through said freezing sections, a return pipe for returning the refrigerant to said receiver, and means setting up a limited amount of resistance to flow of said refrigerant for maintaining complete distribution of refrigerant through all of said sections.

14. In combination, a pit large enough to serve as a swimming pool, an easily mountable and demountable frame structure in said pit, a feed header, a return header, a plurality of freezing sections supported on said frame structure below the top of said pit and connected to said headers, a receiver connected to the outlet of said return header, means for creating from said receiver a forced circulation of refrigerant through said freezing sections, a return pipe for returning the refrigerant to said receiver, and a yieldable restricting valve in said return pipe operable to set up resistance to flow of refrigerant for maintaining complete distribution of refrigerant through all of said sections.
